Patented Oct. 23, 1923.

UNITED STATES PATENT OFFICE.

JOSE M. BAYOT, OF URBANA, ILLINOIS.

INTERMITTENT-CIRCUIT-CLOSING SWITCH.

Application filed September 18, 1922. Serial No. 588,984.

To all whom it may concern:

Be it known that I, JOSE M. BAYOT, a citizen of the United States of America, residing at Urbana, in the county of Champaign and State of Illinois, have invented new and useful Improvements in Intermittent-Circuit-Closing Switches, of which the following is a specification.

In carrying out the present invention it is my purpose to improve and simplify the general construction of intermittent circuit closing switches and to provide a switch of this character which will embody comparatively few parts and these so arranged and correlated as to reduce the possibility of derangement to a minimum.

It is also my purpose to provide an intermittent circuit closing switch wherein the speed of the switch, when operated to intermittently close the circuit, will be so regulated as to enable the intervals between the closing of the circuit to be of practically the same length, thereby enabling the switch to operate uniformly and evenly.

With the above recited objects in view, and others of a similar nature, the invention resides in the construction, combination and arrangement of parts set forth in and falling within the scope of the appended claim.

In the accompanying drawings:

Figure 1 is a vertical sectional view through my intermittent circuit closing switch.

Figure 2 is a horizontal sectional view on the line 2—2 of Figure 1.

Figures 3, 4 and 5 are perspective views showing details of the invention.

Referring now to the drawings in detail, 1 designates a casing or housing which, in 40 the present instance, is cylindrical in cross section. Suitably fastened to the housing 1 within the same is a semi-cylindrical block 2 of a length corresponding to the length of the casing. One end of the casing 1 is 45 closed by a suitable cover 3 which may be ornamented, as shown in Figure 1 of the drawing. This cap or cover 3 is formed centrally with an opening, and within the opening is a bushing 4. Sliding within the 50 bushing 4 is a push button 5. The inner end of the push button 5 is connected with one end of a plunger 6 which, in this instance, is square in cross section and slidably mounted within a guide strip 7 carried by the flat face of the semi-cylindrical block 2. Connected to one side of the

plunger rod 6 and extending downwardly and outwardly therefrom are spring arms 7, the outer ends of which terminate in alignment with each other, and fastened to the outer ends of the spring arms 7 is a rack bar 8 that meshes with a pinion 9 mounted upon a stud 10 carried by the flat face of the block 2. Also mounted upon the stud 10 and fastened to the pinion 9 is a spur gear 11 60 that meshes with a pinion 12 rotatably mounted upon a stud 13. This pinion 12 carries governor vanes 14, the rotation of which are resisted by the air as the pinion 12 revolves. Secured to the inner side of the cover 3 is a hook 15 and to this hook 15 is connected one end of a retractile spring 16. The other end of the spring 16 is secured to the plunger rod 6, as at 17.

When the push button 5 is pressed by the hand of the operator, the plunger rod 6 moves inwardly, and in this movement of the plunger rod the rack 8 being mounted upon the spring arms 7, slides over the pinion 9. The spring 16 is stretched as the plunger rod moves inwardly, and upon the release of the push button the spring 16 reacts to draw the plunger rod 6 outwardly. In this outward movement of the plunger rod the rack 8 meshes with the pinion 9 and so rotates the pinion 9 and the spur-gear 11, and as the latter revolves motion is transmitted to the pinion 12, thereby rotating the vanes 14. These vanes 14, on account of the air resistance, retard the outward movement of the plunger rod 6 under the action of the spring 16, so as to prolong the movement of the plunger rod and at the same time render such movement even and uniform.

Secured to the flat face of the block 2, and extending outwardly therefrom, is a stud 18 located at the side of the plunger bar 6 remote from the rack 8, and pivoted upon this stud 18 is a V-shaped casting 19, clearly illustrated in Figure 5 of the drawings. This casting comprises a sleeve 20 that encircles the stud 18, a leg 21 and a leg 22 integral with the sleeve 20 and offset from the leg 21, the legs 21 and 22 describing a V with the sleeve 20 forming the apex of the V. The leg 21 at its outer end lies alongside the plunger bar 6 between the latter and the flat face of the block 2, and such end of the leg 21 is equipped with a disk 23 formed of felt or analogous material, which lies in frictional engagement with the

adjacent side of the plunger rod 6, as clearly shown in Figure 2 of the drawings. The leg of the casting extends between a pair of spaced stop pins *a* and *a'*, carried by the semi-cylindrical block 2, whereby the swinging movement of the casting is limited. The other leg 22 at its outer end is equipped with an outwardly extending contact finger 24. Fastened to the plunger bar 6 are contact strips 25 spaced apart, and in the present instance two in number. In this instance each contact strip 25 is L-shaped, and one leg fits in an opening 26 formed in the plunger bar 6, while the other leg lies alongside and in contact with the side of the plunger bar 6 facing the contact finger 24.

In the present instance, the hook 15 and the stud 18 are connected in the circuit in which my improved intermittent contact switch is installed and the hook is electrically connected to the contacts 25.

When the plunger is depressed, as previously described, the casting 19 swings downwardly and the contact finger 24 away from the contact 25, this downward movement of the casting 19 being due to the frictional contact between the disk 23 on the leg 21 and the plunger bar 6, this swinging movement being limited by the stop pins *a* and *a'*. Upon the release of the plunger the casting 19 is swung in the other direction, incident to the frictional contact between the disk 23 and the plunger bar and in the initial movement of the plunger bar the casting 19 is restored to normal position, while in the continued movement of the bar the contacts 25 rub over the con-

tact 24, thereby intermittently closing and opening the circuit in which my improved switch is located.

I have entered into a detailed description of the construction and relative arrangement of parts embraced in the present and preferred embodiment of my invention with a view to imparting a full, clear and exact understanding of the said embodiment. I do not desire, however, to be understood as confining myself to the said specific construction and relative arrangement of parts, inasmuch as in the future practice of my invention such changes or modifications may be made as fairly fall within the scope of my invention as defined by my appended claim.

Having thus described the invention, what is claimed as new, is:—

An intermittent circuit closing switch comprising a support, a push rod on said support mounted for sliding movement, a push button on said rod whereby the rod may be pushed in one direction, means for sliding said rod in the opposite direction upon the release of said push button, an intermittent contact device operated by said rod in its last movement, comprising a V-shaped casting pivoted at its bight and having one leg offset from the other and engaging said rod, a contact finger carried by the other leg and contacts on said rod spaced apart and engageable with said finger in the movement of said rod upon the release of said push button.

In testimony whereof I affix my signature.
JOSE M. BAYOT.
